1

This invention relates to reciprocating plunger or piston pumps and more particularly to multiple pumps of the radial type adapted to deliver either solid or liquid lubricant or thixotropic solids or liquids to a number of different points. Such lubricants and thixotropic solids and liquids will hereinafter be referred to as "grease."

Various types of radial multiple grease pumps are known and these known types for the most part include a number of pump elements which are arranged radially around a rotary operating shaft which is provided with a common cam arranged to operate the plunger of each pump element, in turn. This construction, while being very compact and comprising a simple mechanism, suffers from the disadvantage that there is inevitably a considerable amount of side thrust on the pump plungers due to friction and also to the circumferential component of the cam thrust, particularly during the outward or discharge stroke of the plungers.

It is, accordingly, an object of the present invention to provide a multiple pump of the type in which the pump elements are arranged radially around a central actuating shaft and in which side thrust on the plungers is reduced or eliminated.

In accordance with the present invention, a multiple plunger or piston pump comprises a number of individual pump elements arranged in radial and circumferentially spaced relationship around the axis of rotation of a driving member, each pump plunger, or each set of associated pump plungers, being actuated in turn by means of a turnable and reciprocable plunger-actuating member which, by an operative connection with the driving member, is brought consecutively into each of its plunger-operating positions, in each of which its turnable motion is stopped temporarily and in each of which it is directly in line with one pump element, or one set of associated pump elements, and which, by a further operative connection with the said driving member, is made to reciprocate so as to cause the plunger, or plungers, of the pump element, or set of associated pump elements, to carry out its, or their, discharge and suction strokes, whereafter the plunger-actuating member is again turned so that it faces the succeeding pump element, or set of associated pump elements, and then repeat the cycle of operations.

In one construction, the said plunger-actuating member is caused to reciprocate toward and away from the pump plungers by a direct connection

2

with a driving shaft which is continuously rotated during the operation of the pump.

By a further operative connection with the driving shaft, which includes intermittently-acting transition or indexing mechanism, the said plunger-actuating member is rotated consecutively to face all the pump elements, or all the sets of associated pump elements, in turn in readiness for its plunger-actuating reciprocating movement.

In this construction, the plunger-actuating member is slidably arranged in a housing and is reciprocated relatively to the latter by a crank or eccentric connection with the driving shaft. The housing is mounted upon a member which is turnable around, and relatively to, the driving shaft by indexing mechanism which obtains its movement from a driving member which is rotatable with the shaft and forms part of the said indexing mechanism. The latter is actuated intermittently and means are provided for retaining the housing in any one plunger-operating position until it is required to rotate the said housing into the next succeeding plunger-operating position.

By arranging that the actuating-member housing is brought to rest, or substantially to rest, during all or the major part of the time during which the plunger-actuating member is engaging a pump plunger, or set of associated plungers, the side thrust or at least the greater part of the thrust on the latter is eliminated.

The indexing means for giving the housing a step-by-step rotation may comprise a cam and/or crank mechanism operated from a driving shaft actuated by a main driving member, or it may comprise a planetary or other form of mechanism which derives its motion from the main driving member and transmits motion intermittently to the housing.

If desired, the plunger-actuating member may be arranged to operate two or more pump elements simultaneously at each stroke.

Further constructional features of the invention will be described in the following more detailed description of two constructional forms of the multiple pump.

Two constructional forms of the invention are shown, by way of example, on the accompanying sheets of drawings, whereon:

Figure 1 is a sectional elevation of one multi-pump construction;

Figure 2 is a half sectional plan view of the pump on the line A—A in Figure 1, the indexing mechanism being omitted from the figure;

Figure 3 is a top plan of the pump actuating-bolt housing;

Figure 4 is a sectional elevation of the pump actuating-bolt housing;

Figure 5 is a perspective view of the actuating-bolt;

Figures 6, 6A and 6B are all plan views of the indexing-mechanism on the line B—B in Figure 1, but showing the mechanism in three different operative positions;

Figures 7, 7A and 7B are plan views of the indexing-mechanism on the line A—A in Figure 1, but showing the mechanism in three different operative positions;

Figures 8, 8A and 8B are plan views of the indexing mechanism on the line C—C in Figure 1, but showing the mechanism in three different operative positions;

Figure 9 is a sectional elevation of a modified form of multi-radial pump; and

Figure 10 is a fragmentary section on the line D—D in Figure 9.

Referring first to Figures 1 to 8B:

The multiple pump comprises a substantially cylindrical outer base casing 1 arranged with its axis vertical and divided by a horizontal partition 2 at about its mid-height. The upper portion of the casing above the partition is open, forming the bottom of a reservoir for grease to be pumped.

The lower part of the outer casing 1 below the partition 2 is closed, forming an oil-tight reservoir 3 in which is housed the pump driving mechanism which is described hereinafter. A filling passage closed by a plug 4 is provided through which the reservoir can be filled with oil to lubricate the driving mechanism.

Within the reservoir 3 integral with the partition 2 and spaced from the wall of the outer casing, there is a concentrically arranged skirt or flange 5, to the bottom end of which a bottom plate 6 is attached by set screws 6a, the whole forming an inner chamber within which is arranged the step by step indexing mechanism, as will be described hereinafter. Holes 7 through the skirt or flange and the bottom plate permit the entry of oil from the reservoir 3 to lubricate the mechanism arranged within the inner chamber.

The partition 2 is formed with a central hollow boss 8 in which two axially-spaced ball bearings 9 and 10 are fitted. A hollow sleeve 11 is turnably arranged in the ball bearings, and is formed at its upper end above the partition with a flange 12 on which a cylindrical housing 13 for a plunger-actuating bolt which will be described hereinafter, is mounted, a sealing ring 14 being provided between the flange and the upper face of the boss 8 on the partition. The housing 13 is made up of upper and lower parts 13a and 13b fixed together by screws 13c.

A central operating shaft 15 is rotatably mounted in two axially-spaced ball bearings 16 and 17 of which the bearing 16 is fitted in the sleeve 11, and the bearing 17 in the bottom plate 6 of the inner chamber. A cup-shaped worm wheel member 18 is fixedly mounted upon the bottom end of the operating shaft 15 below the lower ball bearing 17, the vertical rim 19 of the member surrounding the inner chamber and being provided externally with a number of worm teeth 20 which are engaged with a worm 21, see Fig. 2, mounted upon a horizontal driving shaft 22 rotatably arranged in bearing 23 and 24 fitted in housings 25 and 26 mounted in the outer cas-

ing 1. One end of the driving shaft 22 projects out of the casing through an oil-tight bush and is adapted to be driven by an electric motor, belt and pulley or other driving means not shown in the drawings.

Referring particularly to Figs. 3 and 5, as viewed in plan, the above mentioned plunger-actuating bolt 27 is of T-shape and is slidably mounted in the housing 13. The stem 28 of the bolt acts as a ram to actuate the pump plungers 29 and its upper, lower and side surfaces are slidably guided by inner surfaces of the housing. Referring also to Figs. 1 and 4, the cross part 30 of the bolt is also slidably engaged by the housing on its side, upper and lower faces, its side faces being provided with horizontal projecting ribs 31 which are slidable in grooves 32 formed within the housing. The housing thus forms a complete guide for the actuating bolt in its reciprocating movements at right angles to the axis of the operating shaft 15.

The cross part 30 of the bolt is formed on its underside with a longitudinal slot 33 in which is engaged a roller 34 mounted on a crank pin 35 carried by a flange 36 at the upper end of the operating shaft 15, the crank pin being offset from the axis of the shaft. Thus, when the shaft is rotated the roller 34 runs to and fro in the groove 33 and at the same time reciprocates the bolt relative to the housing 13. As mentioned above, the outer surface of the housing is cylindrical and the arrangement is such that the rounded end of the stem 28 of the bolt is substantially flush with this outer surface when the bolt is retracted to its innermost position within the housing.

The upper part of the outer casing above the horizontal partition is formed with two vertically spaced rows of radial holes 36 which are also equidistantly spaced from each other in the circumferential direction. A number of plunger pump units 37, which may, for example, be constructed like those described in my prior United States Patent No. 2,371,054, dated March 6, 1945, are mounted in the radial holes in a radial fashion. The radially-arranged plunger cylinders project into the space in the outer casing above the partition 2, their suction ports 38 communicate with the space, and the heads 39 of their pump plunger 29 are spring urged towards and abut upon the cylindrical surface of the housing 13.

In this particular construction, each row of pumps contains twelve individual pumps, each pump in the lower row being parallel to and immediately below the corresponding pump in the upper row. The outer face of the stem 28 of the actuating bolt 27 is of sufficient height to engage simultaneously the heads 39 of the plungers of two superimposed pumps, one in each row.

The above mentioned indexing mechanism is used for rotating the actuating-bolt housing 13, and the bolt itself from one operative position in which the bolt faces two superimposed pumps to the succeeding position in which the bolt faces the next pair of superimposed pumps. Referring to Figs. 1 and 6 to 8B, the mechanism comprises a two-armed rocker member 40, mounted on the lower face of the hollow sleeve 11 carrying the bolt housing 13. A pivot pin 41 at the end of one arm and spaced from the axis of rotation of the rocker member, projects downwardly from the latter and a gear sector member 42 is pivotally mounted upon it. A roller 43, rotatably mounted on a pin 44 projecting upwardly from the upper

face of the gear sector and spaced from the pivoting axis thereof, is pulled into engagement with the periphery of a cam 45, which is fixed on the operating shaft 15 below the rocker member 40 by means of a tension spring 46 connected between a pin 47 fixed in the extremity of the second arm of the rocker member and a lug 48 on the gear sector 42.

Rotatably mounted on a hollow boss 49 forming part of and projecting downwardly from the cam 45 is a double-armed pawl carrying member 50. One arm 51 is in the form of a gear wheel sector having its axis coaxial with the axis of the sleeve upon which the pawl carrying member is mounted, and is formed with teeth 53 which engage with those of the aforesaid gear sector member 42, and the other arm 51A is provided with a downwardly projecting pin 54 upon which is pivotally mounted a pawl 55 which is urged by a spring 56 into engagement with one or another of a number of recesses 57, Figs. 8 to 8B, formed between the teeth 58 of a ratchet wheel 59 rigidly secured to the bottom plate 6 of the inner chamber. The ratchet wheel has twelve notches and twelve teeth, corresponding to the number of pump units in each row, and the pawl 55 is so arranged that its carrying member 50 is permitted to rotate in the clockwise direction but is prevented from rotating in the counterclockwise direction.

A retaining arm 60 is pivotally mounted at one end below the gear sector 42 upon an extension of the pivot pin 41 upon which the gear sector 42 itself is pivotally mounted. At its mid-length the retaining-arm carries a roller 61 which is pulled into resilient engagement with one of the notches 57 between any two adjacent teeth 58 of the fixed ratchet wheel 59 by means of a tension spring 62 connected between the free end of the arm and an extension of the pin 47 fixed in the extremity of the second arm of the rocker member. The arrangement is such that when the roller 61 is engaged in a notch 57 in the ratchet wheel 59 the stem 28 of the actuating-bolt 27 is in line with one pair of vertically-superimposed pump plungers 29. The retaining arm and roller thus serve to locate the rocker member 40 and with it the housing 13 and actuating-bolt 27 in any of the twelve operative positions of the bolt, but the arrangement is such that if sufficient force is applied the retaining roller 61 can be forced to roll over the teeth of the fixed ratchet wheel, one tooth at a time, against the restraining action of its spring.

Referring to Figs. 6 to 8B, in operation, the operating shaft 15 is rotated at a relatively low speed through the worm gear 20, 21. During the time the operating shaft is making one complete revolution relative to the housing, the roller 34 on the operating shaft crank pin 35 engaging the slot 33 in the actuating-bolt 27 will cause the latter to make one complete forward and backward stroke, thus imparting one delivery stroke and permitting one suction stroke to one pair of vertically-superimposed pump plungers 29.

The cam 45, which rotates with the shaft 15, is so shaped and angularly positioned that, see Fig. 6, just before the above mentioned cycle of operations is completed the ascending face 45a of the cam engages the roller 43 on the gear sector member 42 and the latter is caused to rotate in the clockwise direction about the pin 41 against the action of the spring 46 holding the roller in engagement with the cam. Referring to Fig. 7, as the teeth of the gear sector 42 are

in mesh with the teeth 53 of the pawl carrying member 50, the gear sector tends to rotate the pawl carrying member in the counterclockwise direction about the axis of the operating shaft 15. As previously mentioned, however, the pawl carrying member is prevented from rotating in this direction by the engagement of the pawl 55 with the fixed ratchet wheel 59 as shown in Fig. 8. Consequently, the gear sector 42 is forced to roll on the teeth of the pawl carrying member in an epicyclic manner, thereby causing the pivot pin 41, the rocker member 40, the hollow sleeve 11, the housing 13 and the actuating-bolt 27 to rotate in a clockwise direction, until it assumes the position shown in Fig. 6A. The cam 45 is so shaped that the angular movement thus imparted to these members just corresponds to the angular movement from one notch 57 of the ratchet wheel 59 to the next. As there are as many teeth 58 on the ratchet wheel as there are pumps in each row, it follows that since the actuating-bolt housing 13 is connected to the rocker member 40, the actuating-bolt is brought into position to operate the next pair of vertically-superimposed pump plungers, the roller 61 of the retaining arm 60 being compelled to rise over one tooth in the process.

After the tip 45b of the cam rise has passed the roller 43 on the gear sector 42, as shown in Fig. 6A, the roller engages the descending face 45c of the cam, which permits the gear sector 42, under the action of its spring 46, to rotate in the counterclockwise direction until it assumes the position shown in Fig. 6B. This motion of the gear sector causes the pawl carrying member 50 to rotate clockwise because in this case there is no resistance due to the action of the pawl 55, the latter being withdrawn over one tooth 58 of the ratchet wheel 59 and falling into the next notch 57, see Figs. 7A-7B and 8A-8B.

The engagement of the retaining roller 61, Figs. 8 to 8B with the ratchet wheel 59 is sufficiently positive to hold the rocker member 40, on which the gear sector 42 is pivoted, stationary during this movement of the pawl carrying member. Hence, during the descent of the cam 45, Figs. 6A-6B, and throughout the remainder of the cycle of operations until the base of the cam rise 45a once more engages the gear sector roller 43, as shown in Fig. 6, no motion of the indexing mechanism takes place, but the crank pin 35 and the roller 34 attached to the driving shaft 15 effect a discharge and suction stroke of a pair of pumps as previously described.

Since the rocker member 40 is attached to the hollow sleeve 11 in fixed relationship with respect to the actuating-bolt housing 13 and since the cam 45 is mounted on the operating shaft 15 in fixed relationship with the crank pin 35 and roller 34 which actuate the bolt 27, it follows that the indexing motion to move the bolt from one pair of vertically-superimposed pumps to the next pair always takes place at the same phase in the cycle of operations of the bolt, that is, commencing just before and finishing just after the bolt reaches its inner dead centre. In other words, the rotational or indexing movement of the bolt housing 13 starts just before the inward return stroke of the bolt 27 is completed and finishes just after the outward stroke of the bolt to operate the next pair of vertically-superimposed pumps has begun.

The heads 39 of the pump plungers 29 are normally held by the plunger springs in engagement with the outer cylindrical surface of the actu-

ing-bolt housing 13, the only exceptions being those pump plungers which are in line with the bolt 27 and are being actuated by the latter.

Since the indexing movement starts just before the plunger inward or return stroke is completed and finishes just after the next outward stroke has begun, the actuating bolt must start to move sideways just before completing its stroke. Hence in order to avoid shock it is desirable that as it moves clear of a pair of plungers the face of the bolt should be just flush with the outer surface of the housing as mentioned above.

Although when the plunger heads 39 are engaging the outer surface of the bolt housing 13 the loads on the plunger springs are not great, nevertheless twenty-four such plungers pressing upon the housing do impose an appreciable total frictional load. The effect of this friction on each plunger is also to impose a side thrust. It is true that the side thrust is only small, and that it occurs only at or near the end of the pump stroke when the plunger is stationary, or nearly so, and not throughout the length of the stroke as occurs in known pumps of this type. Nevertheless, it is the object of this invention to eliminate side thrust entirely. Hence, in a modified construction, retaining flanges are provided which are adapted to engage the plunger heads 39 and hold them clear of the cylindrical surface of the actuating bolt housing 13, and also, of course, clear of the actuating bolt stem 28 during the transition movement from one pair of pumps to the next. Referring to Fig. 9, the flange for engaging the lower row of pumps may be constituted by an upward extension 70 of the central boss 8 of the partition 2, and the flange for engaging the upper row of pumps may be constituted by a downwardly-extending rim 71, formed round the inner edge of an annular apertured member 72 mounted in the upper part of the pump outer base casing.

As has been stated above, the top of the outer base casing is open, and, preferably it is fitted with a cylindrical extension 73, which, together with the upper part of the outer base casing above the partition 2, forms a reservoir for the grease or other lubricant to be pumped. The above mentioned sealing ring 14 arranged between the flange on the rotatable hollow sleeve 11 and the upper surface of the central boss 8 on the partition prevents the lubricant in the upper part penetrating through and becoming mixed with the oil in the lower part wherein the driving and indexing mechanisms are situated.

Other forms of indexing mechanism may be used, and a modification of the invention will now be described in which an indexing mechanism of planetary type is used.

Referring to Figs. 9 and 10, this construction differs from that which has been described above in a number of respects. The hollow sleeve 11a carrying the actuating-bolt housing 13a is made of sufficient length to extend right through the inner chamber and is rotatably supported in a ball bearing 74 which is mounted in the central boss 8a of the partition 2a, and a lower ball bearing 74a which is mounted in the bottom plate 6a of the inner chamber, the plate preferably being integral with the skirt or flange 5a forming the side wall of the chamber.

The pump operating shaft 15a is rotatably mounted within the hollow sleeve 11a, by means of ball bearings 75 and 75a fitted adjacent to the top and bottom ends of the sleeve. At its upper end the shaft 15a carries a crank pin 35a and a roller 34a thereon adapted to actuate the

actuating-bolt 27a, as in the previously-described construction. At its lower end the shaft carries a worm wheel 19a having teeth 20a and which is driven by a worm 21a on the driving shaft 22a also in the manner described above.

The skirt or wall of the inner chamber 5a, which again may be formed with holes 5b for lightening purposes is formed with an external spur ring 77 which in this particular case has 48 teeth. An arm 78 is fixedly attached to the bottom end of the rotatable hollow sleeve 11a and carries at its free end a pin 79 on which a planet pinion 80 is rotatably arranged. This pinion is divided axially into two zones, the lower of which has eight teeth 80a which mesh with the teeth of the spur ring 77 on the inner chamber. In the upper zone of the pinion, however, every alternate tooth, is cut away leaving four spaced teeth 80b.

10 The inner surface of the rim 19a of the worm wheel engages both zones of the planet pinion. Facing the upper zone the rim is formed with a plain cylindrical internal face 81 which, by engaging an adjacent pair of the four teeth 80b

15 in the upper zone of the pinion, prevents the latter from turning. Four teeth 82 adjacent to one another are, however, cut in the inner surface of the worm wheel rim, the depth of these teeth being equal to the full depth of the planet

20 wheel and thus engaging both zones of the latter. Except where these teeth occur, the lower part of the rim is cut away so as to clear the teeth in the lower zone of the pinion.

The operation of this mechanism is as follows. 35 Since the plain cylindrical part 81 of its rim is clear of the teeth 80a of the lower zone of the planet pinion it follows that as the worm wheel rotates, no drive is thereby transmitted to the planet pinion. Moreover, the plain cylindrical part 81 of the rim engaging two teeth in the upper zone of the planet pinion acts as a positive lock for the latter.

When, however, the set of four teeth 82 in the rim of the worm wheel reaches the planet pinion, the recesses between these teeth provide clearance for the teeth 80a in the upper zone of the planet pinion thus freeing it of its lock and allowing it to be rotated by the teeth 82 in the lower part of the rim 19a which engage the teeth 80a in the lower zone of the planet pinion. Consequently, as the planet pinion is rotated, it rolls round the spur ring 77 in epicyclic fashion by an amount corresponding to four teeth, or, in other words, it covers a twelfth of a revolution, or 30°. The planet pinion being mounted on the arm 78 thus acts to turn the hollow sleeve 11a and the housing 13a for the actuating-bolt 27a by this amount, bringing the face of the bolt stem opposite to a fresh pair of vertically-superimposed pumps.

The movement of the housing and bolt stops when the four teeth 82 on the rim of the worm wheel have passed beyond the planet pinion, which latter will again be locked against rotation by the engagement of the plain cylindrical surface 81 of the upper zone of the worm wheel rim with two of its teeth. Further rotation of the worm wheel merely continues to rotate the operating shaft 15a, which causes the actuating bolt 27a, to make an inward and outward stroke to operate the appropriate pair of vertically-superimposed pumps.

As in the previously described construction, there is a fixed relationship between the position 75 of the four teeth 82 on the inner rim of the worm

wheel, which effect the indexing movement from one pump piston to the next, and the position of the crank pin 35a and roller 34a which operate the actuating bolt 27a. Thus, the movement of the bolt and its housing 13a from one pair of vertically-superimposed pumps to the next always takes place at the same phase in the cycle of operation of the bolt, and this relationship is so adjusted that the rotation of the housing 13a and bolt 27a always starts just before the inward stroke of the bolt (corresponding to the suction stroke of one pair of pump plungers) is completed and finishes just after the outward stroke (corresponding to the delivery stroke of the next pair of pump plungers) has begun and when the end of the bolt is withdrawn substantially flush with the cylindrical surface of the housing as previously explained.

It will be appreciated that modifications of this planetary mechanism are possible, for example, the planet wheel 80 might be mounted on a fixed spindle projecting vertically downwardly from the partition 2A and the spur ring 77 might be operatively connected to the operating shaft 15A and thereby to the plunger-actuating bolt housing 13A.

It will be realised that in this modification the bolt housing will be intermittently rotated from one plunger-actuating position to the next in a direction opposite to that of the rotation of the operating shaft, but there is no objection to this.

I claim:

1. A multiple element pump of the radial type including in combination a rotatable driving member, a plurality of radially directed, circumferentially spaced individual pump elements arranged about the axis of rotation of said driving member, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, means driven by said driving member and connected to said plunger actuating member to move said plunger actuating member successively into each of its plunger actuating positions in each of which its turning movement is temporarily stopped and in each of which it is aligned with at least one pump plunger, and other means driven by said driving member and connected to said plunger actuating member to reciprocate said plunger actuating member thereby to cause said plunger to carry out its discharge and suction strokes whereafter said plunger actuating member is turned so that it faces the succeeding pump element to repeat the cycle of operation.

2. A multiple element pump of the radial type including in combination a rotatable driving member, a plurality of radially directed, circumferentially spaced individual pump elements arranged about the axis of rotation of said driving member, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, means driven by said driving member and connected to said plunger actuating member to move said plunger actuating member successively into each of its plunger

actuating positions in each of which its turning movement is temporarily stopped and in each of which it is aligned with at least one pump plunger, and other means including means connected to and continuously driven by said driving member for reciprocating said plunger actuating member thereby to cause said plunger to carry out its discharge and suction strokes whereafter said plunger actuating member is turned so that it faces the succeeding pump element to repeat the cycle of operation.

3. A multiple element pump of the radial type including in combination a rotatable driving member, a plurality of radially directed, circumferentially spaced individual pump elements arranged about the axis of rotation of said driving member, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, an indexing mechanism operated by said driving member and connected to said plunger actuating member for intermittently turning said actuating member to successive positions in each of which said actuating member is aligned with at least one pump plunger, and means driven by said driving member and connected to said plunger actuating member to reciprocate said plunger actuating member thereby to cause said plunger to carry out its discharge and suction strokes whereafter said plunger actuating member is turned so that it faces the succeeding pump element to repeat the cycle of operation.

4. A multiple element pump of the radial type including in combination a rotatable driving member, a plurality of radially directed, circumferentially spaced individual pump elements arranged about the axis of rotation of said driving member, said pump element including means forming a cylinder having an inlet and an outlet and having a pump plunger reciprocable in said cylinder and adapted to control the entry of grease into and the discharge of grease from said cylinder, a housing turnably arranged relative to said pump elements on said axis of rotation, a plunger actuating member carried by said housing and mounted for reciprocation therein, means driven by said driving member and connected to said housing for intermittently turning said housing and said plunger actuating member, to successive positions in each of which said actuating member is aligned with at least one pump plunger, and other means driven by said driving member and connected to said plunger actuating member to reciprocate said plunger actuating member in said housing thereby to cause said plunger to carry out its discharge and suction strokes whereafter said housing is turned so that said plunger actuating member faces the succeeding pump element to repeat the cycle of operation.

5. A multiple element pump of the radial type including in combination a rotatable driving member, a plurality of radially directed, circumferentially spaced individual pump elements arranged about the axis of rotation of said driving member, each pump element including means forming a cylinder having an inlet and an outlet and having a pump plunger reciprocable in said cylinder and adapted to control the entry of grease into and the discharge of grease from said cylinder, a housing turnably arranged

11

relative to said pump elements on said axis of rotation, a plunger actuating member carried by said housing and mounted for reciprocation therein, an indexing mechanism operated by said driving member and connected to said housing for intermittently turning said housing and said plunger actuating member to successive positions in each of which said actuating member is aligned with at least one pump plunger, and crank means driven by said driving member and connected to said plunger actuating member to reciprocate said plunger actuating member in said housing thereby to cause said plunger to carry out its discharge and suction strokes whereafter said housing is turned so that said plunger actuating member faces the succeeding pump element to repeat the cycle of operation.

6. A multiple element pump of the radial type including in combination a rotatable driving shaft, a plurality of radially directed, circumferentially spaced individual pump elements arranged about the axis of rotation of said shaft, each pump element including means forming a cylinder having an inlet and an outlet and having a pump plunger reciprocable in said cylinder and adapted to control the entry of grease into and the discharge of grease from said cylinder, a plunger actuating member, guide means for said plunger actuating member and in which the latter is mounted for reciprocation, means connected to said guide means for intermittently turning said guide means and said plunger actuating member to successive positions in each of which said actuating member is aligned with at least one pump plunger, said means including a motion initiating member rotatable with said shaft and adapted to actuate said means on each revolution of said shaft, and other means driven by said shaft and connected to said plunger actuating member to reciprocate said actuating member upon each revolution of said shaft thereby to cause said plunger to carry out its discharge and suction strokes whereafter said guide means is turned so that said plunger actuating member faces the succeeding pump element to repeat the cycle of operation.

7. A multiple element pump of the radial type including in combination a rotatable driving shaft, a plurality of radially directed, circumferentially spaced individual pump elements arranged about the axis of rotation of said shaft, each pump element including means forming a cylinder having an inlet and an outlet and having a pump plunger reciprocable in said cylinder and adapted to control the entry of grease into and the discharge of grease from said cylinder, a plunger actuating member, guide means for said plunger actuating member and in which the latter is mounted for reciprocation, means connected to said guide means for intermittently turning said guide means and said plunger actuating member to successive positions in each of which said actuating member is aligned with at least one pump plunger, means for retaining said guide means and said plunger actuating member in said positions, said turning means including a motion initiating member rotatable with said shaft and adapted to overcome the effect of said retaining means and to actuate said turning means on each revolution of said shaft, and other means driven by said shaft and connected to said plunger actuating member to reciprocate said actuating member upon each revolution of said shaft thereby to cause said plunger to carry out

12

its discharge and suction strokes whereafter said guide means is turned so that said plunger actuating member faces the succeeding pump elements to repeat the cycle of operation.

8. A multiple element pump of the radial type including in combination a rotatable driving shaft, a plurality of radially directed, circumferentially spaced individual pump elements arranged about the axis of rotation of said shaft, each pump element including means forming a cylinder having an inlet and an outlet and having a pump plunger reciprocable in said cylinder and adapted to control the entry of grease into and the discharge of grease from said cylinder, a plunger actuating member, guide means for said plunger actuating member and in which the latter is mounted for reciprocation, means connected to said guide means and adapted to turn said guide means the distance between adjacent circumferentially spaced pump elements, a motion initiating member rotatable with said shaft and engageable with said means to actuate said means to advance said guide means, a fixed ratchet wheel having a notch for each circumferentially spaced pump element, a locking member carried by said means and adapted to engage in successive notches to retain said guide means in each position between movements initiated by said motion initiating member, whereby said guide means is intermittently turned to successive positions in each of which said plunger actuating member is aligned with at least one pump plunger, and other means driven by said shaft and connected to said plunger actuating member to reciprocate said actuating member upon each revolution of said shaft thereby to cause said plunger to carry out its discharge and suction strokes whereafter said guide means is turned so that said plunger actuating member faces the succeeding pump element to repeat the cycle of operation.

9. A multiple element pump as claimed in claim 1 wherein said rotatable driving member comprises a rotatable shaft, and including means for driving said shaft including a reduction gearing.

10. A multiple element pump of the radial type including in combination a rotatable driving shaft, a plurality of radially directed, circumferentially spaced individual pump elements arranged about a common axis, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plunger, said actuating member being turnable about said common axis, means driven by said shaft and connected to said plunger actuating member to turn said plunger actuating member successively into each of its plunger actuating positions in each of which its turning movement is temporarily stopped and in each of which it is aligned with at least one pump plunger, and other means including means connected to and continuously driven by said shaft for reciprocating said plunger actuating member thereby to cause said plunger to carry out its discharge and suction strokes whereafter said plunger actuating member is turned so that it faces the succeeding pump element to repeat the cycle of operation.

11. A multiple element pump of the radial type including in combination a rotatable driving member, a plurality of radially directed individ-

ual pump elements, said pump elements being arranged in circumferentially spaced sets of at least two elements arranged about a common axis, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, means driven by said driving member and connected to said plunger actuating member to turn said plunger actuating member successively into each of its plunger actuating positions in each of which its turning movement is temporarily stopped and in each of which it is aligned with the pump plungers of one set of pump elements, and other means driven by said driving member and connected to said plunger actuating member to reciprocate said plunger actuating member thereby to cause said plungers to carry out their discharge and suction strokes whereafter said plunger actuating member is turned so that it faces the succeeding set of pump elements to repeat the cycle of operation.

12. A multiple element pump as claimed in claim 1 wherein said means for moving said plunger actuating member into its successive positions comprises an indexing mechanism of the planetary type.

13. A multiple element pump of the radial type including in combination a rotatable driving shaft, a plurality of radially directed, circumferentially spaced individual pump elements arranged about a common axis, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, a turnable carrier means in which said plunger actuating member is mounted, a planet pinion carried by and turnable with said carrier means, a fixed toothed ring in engagement with said pinion, a rotatable annular driving member connected to said shaft, said annular driving member having a toothed sector adapted to engage and rotate said planet pinion thereby to turn said carrier means and said plunger actuating member whereby said plunger actuating member is brought into successive positions in each of which it is aligned with at least one pump plunger, and means driven by said shaft and connected to said plunger actuating member to reciprocate said plunger actuating member thereby to cause said plunger to carry out its discharge and suction strokes whereafter said plunger actuating member is turned so that it faces the succeeding pump element to repeat the cycle of operation.

14. A multiple element pump of the radial type including in combination a rotatable driving shaft, a plurality of radially directed, circumferentially spaced individual pump elements arranged about the axis of rotation of said shaft, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, a turnable carrier means in which said plunger actuating member is mounted, a rotatably mounted

planet pinion carried by and turnable with said carrier means, a fixed toothed ring in engagement with said pinion, a rotatable annular driving member connected to said shaft, said annular driving member having a toothed sector adapted to engage and rotate said planet pinion thereby to turn said carrier means and said plunger actuating member whereby said plunger actuating member is brought into successive positions in each of which it is aligned with at least one pump plunger, said pinion and said annular driving member being constructed to lock said pinion against rotation except when engaged by said toothed sector so as to prevent inadvertent turning of said plunger actuating member, and means driven by said shaft and connected to said plunger actuating member to reciprocate said plunger actuating member thereby to cause said plunger to carry out its discharge and suction strokes whereafter said plunger actuating member is turned so that it faces the succeeding pump element to repeat the cycle of operation.

15. A multiple element pump of the radial type including in combination a rotatable driving shaft, a plurality of radially directed, circumferentially spaced individual pump elements arranged about the axis of rotation of said shaft, each pump element including means forming a cylinder having an inlet and an outlet and having a pump plunger reciprocable in said cylinder and adapted to control the entry of grease into and the discharge of grease from said cylinder, a turnable and reciprocable plunger actuating member for actuating said pump plungers, a turnable carrier means in which said plunger actuating member is mounted, a rotatably mounted planet pinion carried by and turnable with said carrier means, a fixed toothed ring in permanent engagement with said pinion and about which said pinion is turned, a rotatable annular driving member connected to said shaft, said annular driving member having a toothed sector adapted to engage and rotate said planet pinion thereby to turn said carrier means and said plunger actuating member whereby said plunger actuating member is brought into successive positions in each of which it is aligned with at least one pump plunger, said annular driving member having a smooth inner circumferential surface between the outer ends of said sector, said pinion having a portion provided with less than a full complement of teeth for engagement with said smooth surface to lock said pinion against rotation except by said sector, and means driven by said shaft and connected to said plunger actuating member to reciprocate said plunger actuating member thereby to cause said plunger to carry out its discharge and suction strokes whereafter said plunger actuating member is turned so that it faces the succeeding pump element to repeat the cycle of operation.

16. A multiple element pump of the radial type including in combination a main pump casing, a partition dividing said casing into a pump chamber and a mechanism chamber, a plurality of radially directed, circumferentially spaced individual pump elements mounted in said housing in said pump chamber about a common axis, each pump element comprising means forming a cylinder having an inlet communicating with said pump chamber and an outlet and having a pump plunger reciprocable in said cylinder and adapted to control the entry of grease into and the discharge of grease from said cylinder, a turnable and reciprocable plunger actuating member for

actuating said pump plungers, said plunger actuating member being mounted within said pump chamber, a driving member rotatably mounted in said mechanism chamber, means driven by said driving member and having a part rotatably projecting through said partition and sealed thereagainst and connected to said plunger actuating member to turn said plunger actuating member successively into each of its plunger actuating positions in each of which its turning movement is temporarily stopped and in each of which it is aligned with at least one pump plunger, and other means driven by said driving member and projecting into said pump chamber for connection with said plunger actuating member to recipro-

cate said plunger actuating member thereby to cause said plunger to carry out its discharge and suction strokes whereafter said plunger actuating member is turned so that it faces the succeeding pump element to repeat the cycle of operation.
